(57) **CLAIM**

The ornamental design for a gaming machine, as shown and described.

DESCRIPTION

FIG. 1 is a front right top perspective view of a gaming machine showing our new design;

FIG. 2 is a top view thereof;

FIG. 3 is a bottom perspective view thereof;

FIG. 4 is a front view thereof;

FIG. 5 is a right side view thereof;

FIG. 6 is a rear view thereof;

FIG. 7 is a left side view thereof;

FIG. 8 is a bottom view thereof;

FIG. 9 is a cross-section view thereof taken through line 9-9 of FIG. 2;

FIG. 10 is a front perspective view of the gaming machine of FIGS. 1-9 with the stand shown in an alternate position;

FIG. 11 is a bottom perspective view thereof;

FIG. 12 is a front view thereof;

FIG. 13 is a right side view thereof;

FIG. 14 is a rear view thereof;

FIG. 15 is a left side view thereof;

FIG. 16 is a top view thereof; and,

FIG. 17 is a bottom view thereof.

The broken lines depicting the remainder of the gaming machine illustrates environmental structure and form no part of the claimed design. The curved oblique line shading shows that the surface is a transparent, translucent, highly polished or reflective surface.
